UNITED STATES PATENT OFFICE.

VOTAW S. DURBIN, OF ST. LOUIS, MISSOURI.

RAILWAY-CAR COUPLING.

1,203,319.

Specification of Letters Patent. Patented Oct. 31, 1916.

Application filed June 23, 1915. Serial No. 35,786.

To all whom it may concern:

Be it known that I, VOTAW S. DURBIN, a citizen of the United States, residing in the city of St. Louis and State of Missouri, have invented new and useful Improvements 5 in Railway-Car Couplings, of which the following is a specification.

This invention relates to certain new and useful improvements in railway-car couplers, and has for its object to provide a 10 novel construction whereby the couplers are enabled to stand a greater pulling strain than car couplers of the types now in common use.

With the advent of all-steel cars, coupled 15 with the great length of trains, especially freight trains, which modern improvements in engines has made it possible to utilize, it has been found necessary to increase the 20 strength of the couplers to meet the added strain of the increased load of the trains. With the strongest couplers now in use, however, it very frequently occurs that one or the other of the knuckles of the coupler 25 will pull out owing to the knuckle pin being unable to withstand the strain and breaking. One means of increasing the ability of the coupler to withstand a pulling strain has been to provide the knuckle with a 30 tongue provided at its rear end with a hook which in operation is adapted to engage behind the locking pin. Such construction is shown in Letters-Patent No. 1,000,591, dated August 15th, 1911, granted to J. F. Durbin and myself. In such construction the locking pin will take practically all of the strain off of the knuckle pin and under any circumstances supplements the resistance of the latter offered to the pull against the knuckle. The 40 construction above referred to has in actual practice been demonstrated to be capable of withstanding a far greater pulling strain than other standard types of coupler with which it was placed in competition. While the construction of the patent referred to 45 represented a great advance in the art, it was found that when subjected to a pulling strain approaching 300,000 pounds the hook engaging behind the locking pin would frequently break off, throwing upon the 50 knuckle pin the work of resisting the pull, which, of course, it would be unable to do, and accordingly break off.

The improvements set forth in the present 55 invention have, in actual test, enabled the couplers to withstand a pulling strain

greatly exceeding 300,000 pounds; and hence a car coupler constructed according to this invention can be depended upon to withstand a pulling strain far in excess of 60 that which any coupler now in use, of which I am aware, is able to withstand.

My invention is particularly designed for car couplers of the automatic type such as illustrated in the patent above referred to, 65 but is not necessarily limited to such type of car coupler.

The characteristic feature of a car coupler constructed according to the present invention is that of interengaging flanges or ribs 70 and grooves provided, respectively, on the tongue of the knuckle and the walls of the coupler head, and so arranged as to permit the ready movement of the knuckle in opening and closing, and while in the closed position affording a firm resistance to the pull of the knuckle.

A clearer understanding of the invention, together with features of construction contributing to the attainment of the main purpose thereof may be had from reading the 80 following description in connection with the drawings.

In said drawings.—Figure 1 is a view of two coupler heads in position to be coupled, 85 the coupler head at the left being shown in top plan, and the knuckle thereof being in an open position, and the coupler head at the right being shown in horizontal section with the knuckle thereof locked in the closed position; Fig. 2 is a section on the line 2—2 of Fig. 1, and viewed in the direction of the arrows; Fig. 3 is a section on the line 3—3 of Fig. 1, and viewed in the direction of the arrows; Fig. 4 is a section on the line 4—4 90 of Fig. 1, and viewed in the direction of the arrows; and Fig. 5 is a view of the coupler head at the right of Fig. 1 with the knuckle and coöperating parts removed to illustrate the construction of the locking groove in the 95 bottom wall of the coupler head.

Referring now to these drawings, the numerals 1, 2, indicate corresponding coupler heads of the standard type, each head having mounted therein, on a knuckle pin 3, 100 a knuckle 4, having a tongue 5 which is provided at its rear end with a hook 6. The hooks 6 of the respective knuckles are adapted to engage behind locking pins 7, these parts being of the usual or any preferred 105 construction.

As the construction of each coupler head

- 1, 2, is identical the further description of the invention will deal with only one coupler head, that shown at the right of Fig. 1 being particularly selected for this purpose.
- 5 The coupler head is hollow and projecting upward from the bottom thereof is an inclined ridge 8 which is provided with a curved groove 9, the walls whereof are inclined in opposite directions to the vertical.
- 10 The portion of this ridge on the side of the groove 9 nearest the outer edge of the coupler head provides a curved inclined bearing 10 which is of helicoid form, and which preferably rises gradually from the outer 15 edge of the coupler to the side wall thereof, as more clearly indicated in Fig. 5. The inner wall 11 of the groove 9 is struck on a curve concentric with the center of the aperture 12 which accommodates the knuckle pin 20 3; the outer wall 13, however, being struck on a curve eccentric to the curve of the inner wall 11, for a purpose to be presently explained.
- The numeral 14 indicates a recess which is 25 provided in the under side of the tongue 5 immediately over the bearing 10, and housed in this recess is an anti-friction roller 15 which is supported on an axle pin 16. Projecting from the under side of the tongue 5 30 is a curved flange 17 having its sides inclined to the vertical to correspond with the incline of the walls of the groove 9, and which extends from side to side of the tongue and is adapted, when the knuckle 4 is in 35 the closed position, indicated at the right of Fig. 1, to fit snugly within the groove 9 but so as not to bind against the walls thereof. As shown by Fig. 5, the groove 9 gradually decreases in width from its outer to 40 its inner end, and the flange 17 will therefore correspondingly taper from its outer to its inner end. The body of the tongue 5 above the flange 17 is longitudinally bored, as indicated at 18, the bore extending across 45 the recess 14, and in this bore is loosely mounted the axle pin 16. The inner end of said axle pin is screw-threaded, as indicated at 19, and the roller 15 and the axle pin 16 are maintained in position by first 50 inserting the roller in the recess 14, and then inserting the axle pin 16 into the bore 18 and passing it through said roller and screwing its end through a nut 20 inserted in the recess with said roller.
- 55 The under side of the top of the head 2 is provided with an inclined or helicoid ridge 21 extending from the outer edge of the head to the side wall thereof, said ridge being provided in its under side with a curved 60 groove 22 having inclined walls. The upper side of the tongue 5 is provided with a curved or helicoid flange 23, shown at the right of Fig. 1, having its sides inclined to correspond with the incline of the walls of 65 the groove 22, extending from side to side

of the tongue 5 and adapted to fit snugly within the groove 22 in the same manner as the flange 17 fits in the groove 9. The grooves 9 and 22 and the flanges 17 and 23 are substantially the same in shape and dimensions, so that the illustration of the groove 9 in Fig. 5 on the bottom of the head may be considered to correctly illustrate the shape and dimension of the groove 22 in the top of the head, and the illustration 70 of the flange 23 on the upper side of the tongue 5, shown at the right of Fig. 1, may be considered to clearly illustrate the shape and dimensions of the flange 17 on the under side of the tongue 5.

As shown by Fig. 3, the flange 23 lies directly over the roller 15, which tends to cause the flange 23 to move smoothly and evenly in the groove 22 without binding against either wall thereof, which latter might result to a certain extent if the said roller were located to one side or the other of said flange, which would cause the side of said flange to rest against one or the other of the walls of the groove 22. This result 85 is obviated in connection with the flange 17 by having the roller 15 located adjacent thereto, which acts to hold said flange out of binding contact with the walls of the groove 9.

The portion 24 of the ridge 21 lying nearest the outer edge of the head, and corresponding to the curved bearing 10 of the lower ridge 8, serves as an abutment against which the curved flange 23 engages when the tongue 5 is turned into the coupler head, when the knuckle is turned to the closed position. The portion 10 of the ridge 8 serves a corresponding function in connection with the flange 17. When the knuckle 4 is turned from the open position shown at the left of Fig. 1, to the closed position shown at the right of said figure, the flanges 17 and 23 will enter the respective grooves 9 and 22 and engage behind the curved 100 abutments 10 and 24 which thus afford a strong resistance to the outward movement of the knuckle in a right line under a pulling strain, and in connection with the locking pin 7 practically prevent any strain 105 whatever from coming on the knuckle pin 3. Such flange and groove engagement, therefore, greatly increases the power of the coupler to withstand a pulling strain.

In the movement of the knuckle, in closing or opening, the roller 15 rides upon the surface of the bearing 10 insuring the movement of the knuckle with a minimum of friction and also facilitating the automatic opening of the knuckle when the locking pin 110 7 is raised. It will be understood that in closing the knuckle the roller 15 rides up the inclined bearing 10 and raises the knuckle in the head, as shown at the right of Fig. 2 and in Fig. 3. When the locking 115 pin 7 is lowered, the roller 15 is caused to roll down the bearing 10, thereby causing the knuckle to move in the direction of the arrow 11, as shown at the right of Fig. 2 and in Fig. 3. When the locking 120 pin 7 is raised, the roller 15 is caused to roll up the bearing 10, thereby causing the knuckle to move in the direction of the arrow 12, as shown at the right of Fig. 2 and in Fig. 3. When the locking 125 pin 7 is lowered, the roller 15 is caused to roll down the bearing 10, thereby causing the knuckle to move in the direction of the arrow 13, as shown at the right of Fig. 2 and in Fig. 3.

pin 7 is withdrawn the action of gravity will cause the roller 15 to ride downward on the inclined bearing 10, and thereby cause the tongue 5 to swing outward to move the 5 knuckle 4 to the open position. In this latter movement, and especially if it is accomplished while separating two cars, the tendency would be for the outer sides of the flanges 17 and 23 to bind against the outer 10 walls of the grooves 9 and 22 as the knuckle has a very loose fit upon the knuckle pin 3, and has, therefore, a slight movement independent thereof. By making the outer walls of the grooves 9 and 22 eccentric to 15 the axis of the knuckle pin, the coöperating outer sides of the flanges 17 and 23, in the outward movement of the tongue 5, will be moved away from the outer walls of these grooves and thus binding of the tongues with 20 said walls is prevented. This latter action is further facilitated by the fact that, as the knuckle moves downwardly, as well as outwardly, the incline of the meeting surfaces of the flanges and grooves insures that 25 the former will instantly move out of contact with the walls of the latter in the opening movement of the knuckle.

The bell-crank lever 25 for raising the locking pin 7, and the gravity catch 26 for 30 holding the locking pin when raised, and the control of the latter by the movement of the tongue 5, are all set forth in Letters-Patent No. 1,033,388, granted to J. F. Durbin and myself, dated July 23, 1912, and need not 35 be described herein, as the same form no part of the present invention.

I claim:

1. In a car coupler, the combination of a head having a curved engaging member, and 40 a knuckle rotatably mounted in said head, and having a flange for engaging said engaging member, said flange and said engaging member of helicoid form about the axis of rotation of said knuckle.
2. In a car coupler, the combination of a head having a groove in its bottom, and a knuckle rotatably mounted in said head, and having a tongue on its under side to engage in said groove, the engaging surface of 45 said tongue and said groove inclining correspondingly in a direction longitudinally with the axis of rotation of said knuckle.
3. In a car coupler, a head provided on its

bottom with a curved inclined bearing, and a knuckle mounted in said head and having 55 a tongue adapted to ride on the surface of said bearing and provided on its under side with a curved flange adapted to engage behind said bearing.

4. In a car coupler, a head provided on its 60 bottom with a curved inclined bearing, a knuckle mounted in said head and having a tongue, a roller mounted in said tongue and supported on said bearing, and a curved 65 flange provided on the under side of said tongue and adapted to engage behind said bearing.

5. In a car coupler, a head provided in its 70 bottom with a helicoid groove, one wall whereof is eccentric to the other, and a knuckle mounted in said head and provided on its under side with a helicoid flange 75 adapted to engage in said groove and corresponding substantially in shape and dimensions thereto.

6. In a car coupler, the combination of a head, provided on its top and bottom with curved helicoidal ridges having grooves, and a knuckle rotatably mounted in said head and having a tongue provided on its upper 80 and lower sides respectively with corresponding curved helicoidal flanges to engage in said grooves.

7. In a car coupler, the combination of a head provided on its top and bottom with 85 curved helicoid engaging portions and a knuckle rotatably mounted in said head and provided on its upper and lower sides with correspondingly curved helicoid portions to engage behind said first-mentioned engaging 90 portions, the meeting faces on the sides of said respective portions correspondingly inclined to the vertical.

8. In a car coupler, a head, a knuckle pivotally mounted in said head, said head and 95 knuckle having inclined counterpart interengaging portions curved with respect to the pivotal axis of the knuckle and arranged and adapted to resist strains in a right line when the knuckle is in closed position, and 100 an antifriction bearing between said inclined interengaging portions of said head and knuckle.

In testimony whereof, I have hereunto set my hand.

VOTAW S. DURBIN.
